[57] CLAIM

The ornamental design for an air freshener dispenser or similar article, as shown and described.

DESCRIPTION

FIG. 1 is a top perspective view of an air freshener dispenser or similar article showing my new design, the undisclosed rear elevation being substantially similar in appearance and the dispenser being shown in the "off" position;

FIG. 2 is a bottom plan view thereof; and

FIG. 3 is a top perspective view thereof, showing the dispenser in an "on" position.
